MACHINE KNIFE ADJUSTMENT AND LOCK-
ING DEVICE

Charles E. G. Aff, Jamaica, N. Y.

Application May 31, 1935, Serial No. 24,346

12 Claims. (Cl. 164—58)

This invention relates to improvements in machine knife adjustment and locking devices and has for a principal object the provision of means, partly within the knife body and partly in a separate cooperating member, for positively securing the knife to a member of the machine in which the knife is to be used.

A further object of the invention is the provision in a machine knife of a plurality of transverse 10 oblong holes, each of said holes having communicating therewith a plurality of semi-circular slots and the provision of a bolting member for each of said holes having projections fitting said slots, the engagement of said slots and projections serving 15 to fixedly retain the knife on its support.

Another object of the invention is to provide a bolting member of shorter length than the oblong holes and having fewer projections than the number of slots formed in the knife, whereby 20 the projections may be made to engage several groups of slots in accordance with the adjustment desired.

Still another object of the invention is the provision of a bolting member having fewer projections than the number of slots and having a bolting shaft eccentric to the center axis of the member so that by reversing the position of the member in the hole a finer degree of adjustment 25 of the knife may be obtained.

Still a further object of the invention is the provision in the clamping member of a threaded hole eccentric to the center axis of the member and adapted to be engaged by a bolt extending through the machine member on which the knife 30 is supported.

Another object of the invention is the provision of a machine knife and an extension therefore having a plurality of elongated holes, partly within the knife and partly within the extension, 40 and a plurality of circular slots in transverse relation to, and breaking into, the elongated holes, some of the circular slots being in the knife and others in the extension, the extension being further provided with a projection which members up with the usual relief groove in the knife support; and the provision of a clamping member having projections fitting said semi-circular slots, some of the projections engaging semi-circular 45 slots in the knife and others engaging semi-circular slots in the extension.

Still a further object of the invention is the provision of a knife and an extension bar therefore, the extension bar being provided with a projection engaging the relief slot of the knife support to retain the same in parallel relation to

the face of the knife support and being provided with a cut away portion serving to insure the support of the knife in parallel relation to the face of the knife support.

Other objects will be obvious to those skilled in the art.

In machine knives, such as are used in sheet metal work, squaring shears, etc., such knives being commonly known as "shear blades", in the prior art it has been customary to secure such 10 blades to the shear by means of bolts. The holes in the supporting member were made substantially larger in diameter than the diameter of the bolts so that a limited degree of adjustment can be obtained to compensate for the shortening of the 15 blade due to grinding.

The present invention overcomes this limitation and makes it possible to extend the use of these blades whereby practically all of the cutting steel therein may be utilized.

This invention also enables the blade-maker to produce a reversible blade, thereby making a plurality of cutting edges available in the shear.

Referring to the figures.

Figure 1 is an elevation, partly broken away, 25 showing the new and improved blade and two of the new and improved clamping holes formed therein;

Figure 2 is a sectional view of Figure 1 taken along the lines 2—2;

Figure 3 is a vertical sectional elevation of the new and improved blade taken along the lines 3—3 of Figure 1;

Figure 4 is an isometric view of a new and improved clamping member made in the form of a 35 bolt;

Figure 5 is an isometric view of the new and improved clamping member made in the form of a nut and provided with a bolt;

Figure 6 is a sectional view showing a knife 40 similar to that shown in Figure 1, but provided with an extension bar so arranged that the clamping member engages and secures both the knife and the extension to a shear table;

Figure 7 is a fragmentary isometric view of a 45 knife and extension such as shown in Figure 6;

Figure 8 is a view of a portion of a machine knife having slots formed therein to accommodate a modified form of an improved clamping device;

Figures 9, 10, and 11 are fragmentary views of 50 knives showing the modified clamping member in several different relative positions;

Figure 12 is an end view of the knife and clamp- 55 ing member shown in Figure 11; and

Figure 13 is a transverse sectional view show-

ing a machine knife provided with the improved clamping member secured to a knife bar.

The shear blade 10, which may be provided with cutting edges 11, 12, 13, and 14, is provided with a plurality of oblong holes 15 and 15a, the number of which may vary in accordance with the length of the blade. These oblong holes are provided with flat side surfaces 16 and 17 and semi-circular ends 18 and 19.

10 The surface of the blade, between the cutting faces 11 and 12, is undercut as shown at 20, and the opposite surface, between the cutting faces 13 and 14, is undercut as shown at 21.

15 At right angles to the straight sides of the slots 16 and 17, a plurality of slots 22 are cut in the surface 20 communicating with the slot 15 via the flat side 17. Likewise, a plurality of slots 23 are cut in the surface 20 communicating with the slot 15 via the flat side 16.

20 The slots 22 and 23 are cut with a circular cutter so that their bottoms are curvilinear, as shown in Figure 2.

A clamping member 24 has a body of a similar outline to that of the oblong hole 15, with the exception that its length is shorter than said hole. The member 24 forms a working fit in the hole 15 and due to the fact that it is shorter than the hole it may be positioned therein in any one of several positions.

30 The clamping member is provided with a plurality of projections 25 and 26, fewer in number than the number of slots 22 and 23 communicating with the hole 15. These projections are each of substantially the same outline and form as that of the slots 22 and 23 so that when the member 24 is positioned in the hole 15 or 15a the surface of the clamping member is preferably slightly below the undercut surface 20, as indicated at 27 in Figure 2, when the blade is secured to the shear table.

The clamping member 24 functions as a nut. It is provided with a tapped hole 29 which is eccentric to the center axis of the member 24 so that the member may be turned around with the projections 26 engaging the slots 22 and the projections 25 engaging the slots 23 and thereby finer adjustments of the blade on the shear table may be obtained.

45 The eccentricity of the hole 29 is such that adjustments equal to one half of the spacing apart of the slots 22 and 23 may be obtained and the clearance between the hole 31 in the table 28 and the bolt 30 may be utilized for finer adjustments.

50 In another embodiment of the clamping member, as shown in Figure 4, the member designated by the numeral 24a is provided with projections 25a and 26a and forms the head of a bolt 32 which may be inserted in the oblong holes 15 and by applying suitable hex-nuts the blade may be secured to the shear table 28.

Practically all of the shear tables are provided with clearance slots 33 which are usually spanned by the blade. When the width of a blade becomes so reduced, due to frequent grindings, that it no longer spans the clearance slot 33, it is then impossible to mount the blade in normal parallel relation to the table 28.

In some cases, in order to save expenses, some 55 of the knife owners may purchase blades or shears having a single cutting edge and of shorter width than was originally designed for the machine.

In the modification of the invention shown in 60 Figure 6, a shear blade 34 is shown having a cut-

ting edge 35. This blade is provided with an extension bar 36.

The blade 34 has a bead 37 which matches a bead 38 formed in the extension bar 36. The extension bar is also provided with flat projecting 65 tongues 39 which project from the surface thereof of the depth of the clearance slots 33. A plurality of elongated holes 40 are formed partly in the blade 34 and partly in the extension bar 36. These elongated holes may be identical in form with the holes 15 described above. The holes 40 have communicating therewith a plurality of slots 41 which may be identical with the slots 22 and 23 above described.

When clamping members, such as 24 and 24a, 15 are applied to the elongated holes 40, some of the projections engage slots in the knife 34 and others engage slots in the extension bar 36. By this arrangement the blade and the extension bar are both securely clamped to the shear table 28 and are rigidly held in proper relation to each other by the projections engaging the slots, and the tongue 39 falls within the slots 33 and prevents the blade 34 from "cocking".

The blade 34, shown in Figure 6, is of shorter 25 width than blades such as the blade 10 and the provision of the extension bar or backing bar makes it possible to provide a shear with an inexpensive knife or blade capable of giving good results.

This invention also makes it possible to use two edged blades such as shown in Figures 1, 2 and 3 and by providing in the surface 21 slots identical with the slots 22 and 23, except opposite thereto, four edged blades may be utilized.

It is obvious that two or four edged blades can be produced at less cost per cutting edge than a blade having only one cutting edge. In many existing shears the two or four edged blades cannot be used because of the positions of the bolt holes in the member supporting the blade and in many others, a very limited adjustment is possible because the machines were made to accommodate blades having only one cutting edge.

By providing a knife having slots communicating with the elongated holes and by providing a clamping member or nut having projections matching said slots practically unlimited and most minute adjustments of the blade may be obtained.

In the modification shown in Figure 8, a knife 42 is provided with an oblong depression 43 communicating with one face of the knife and the back edge 44 thereof. A plurality of curvilinear 55 slots 45 formed in the face of the knife communicate with the depression 43 along one side thereof and a plurality of curvilinear slots 46 formed in the face of the knife communicate with the depression 43 along the other side thereof. A hole 47 extends through the webs 48 formed between the slots 45 and a similar hole 49 extends through the webs 50 formed between the slots 46.

An insert member, generally designated by the numeral 51, has an oblong body portion 52 which fits the depression 43 and has a plurality of extensions 53 of similar form to, and adapted to form a fit with, the slots 45; and a plurality of extensions 54 of similar form to, and adapted to form a fit with, the slots 46.

The extensions 53 have borings therein so 70 positioned that when the insert member 52 is located in the depression 43 these borings line up with the hole 47. The extensions 54 are likewise provided with borings which line up with the hole 49 when the insert member 52 is posi-

tioned in the depression 43. The borings in the upper extensions 53a and 54a are tapped with screw threads.

When the insert member 52 is positioned in the depression 43 it is secured to the knife 42 by means of pins 55 and 56. The pin 55 is provided with a threaded portion 57 which is screwed into the extension 53a, and the pin 56 is provided with a threaded portion 58 which may be screwed 10 into the extension 54a.

The insert member 52 has formed therein, at right angles to the flat outer surface thereof, a tapped hole 59 by means of which the knife may be secured to a knife bar 60 or other supporting 15 member by means of cap screws, one of which is shown at 61 in Figure 13.

While only one oblong depression 43 is shown in the drawings, it is obvious that a plurality of such depressions and a plurality of insert members 52 would be required for supporting such blades in a machine. When the width of the blade 42 has been shortened by frequent grindings its use may be extended by means of insert members 52. The insert members may be re- 20 moved and reinserted with the extensions 53a and 54a projecting above the back edge 44 of the blade, as shown in Figure 10, in which case the portions of the insert member 52 extending above the back edge 44 would member up with the knife 25 bar of a machine and act in place of an extension bar such as is shown in copending application 12,423, filed March 22nd, 1935, improvements in Machine knives. By using these insert members in place of extension bars perfect adjustment of 30 the knife in the machine is possible because the adjustments in the pull rods which operate the bar cover a range greater than the spaces from the upper edge of the member and the back edge 44 of the knife.

40 When the knife becomes still shorter by frequent grindings, the insert member 52 may be removed and reinserted in a further raised position such as is shown in Figure 11, and so on.

In Figure 12 an end view of a knife 42 is shown 45 with the insert member 52 positioned the same height as the insert member shown in Figure 11.

The new and improved insert member 52, with its extensions 53 and 54, is, in effect, a tapped hole which may be adjustably applied to a machine knife. This overcomes the necessity of forming a blind tapped hole in machine knives and gives the added feature of an adjustable tapped hole which may be moved relative to the 50 knife to compensate the wear.

55 In the modification shown in Figures 8 to 12, the insert or clamping member provides the equivalent of, so called, "blind bolt holes" in a knife, particularly those used in paper cutting machines. The knife is bolted to the knife bar 60 of the machine without the bolt holes extending through the "face" or side of the knife which, in cutting certain classes of paper, overcomes the following objections:

If the holes extend through this face the edges 65 of the paper being cut "crowd" into these holes and are marked or scored.

This also enables the upper part (that part which protrudes above the back edge of the knife, for instance) of the device to engage and hold 70 an extension bar to the back edge of the knife thereby providing a backing to support the knife as it is lowered to compensate for the decreases in width caused by grinding.

This new and improved device also overcomes 75 the difficulty heretofore encountered due to the

back edge of the knife tilting into the relief groove of the knife bar when the bolts, which hold the knife to the knife bar, are tightened, and prevents the scoring of other parts of the machine which are adjacent to the knife.

The invention contemplates the formation of depressions 43 in the knife and the formation of the slots 45 and 46 therein as well as the holes 47 and 49, at the time the knife is manufactured and the insert members 52 may be applied to 10 any blades as the old ones, with which they are associated, become too worn for further use.

Although simple embodiments of the invention are herein shown and described, it is obvious that many variations of the device may be made without departing from the spirit of the invention as defined in the following claims.

What is claimed is:

1. A machine knife or blade having a plurality of oblong holes formed therein, means defining a plurality of slot depressions in said knife communicating with each of said holes, and means for securing said knife to a machine, said last means including a nut member contained entirely within each of said holes and associated slot depressions and having projections engaging at least some of said slot depressions for retaining the nut members in definite fixed relation to said knife.

2. The invention according to claim 1 in which the nut member is provided with a tapped hole eccentric to its center line so that it may be reversed to obtain finer adjustments than the spacing of the slot depressions.

3. In combination a support, a machine knife or blade having a series of oblong holes formed therein and a series of parallel slot depressions also formed therein communicating with said holes, said slot depressions being disposed in angular relation to at least a portion of the walls defining said holes, clamping members positioned within said holes and having extensions interlocking with said depressions for retaining said blade in definite adjustment relation to said support, said members each having a tapped hole formed therein, and bolts extending through said support and engaging said tapped holes for securing the blade to said support through the medium of said clamping members.

4. A device for adjustably supporting machine knives or blades in a machine comprising an oblong member having a threaded hole formed therein and having a plurality of arms extending therefrom adapted to fit into and engage in interlocked relation a depression of similar shape formed into said blade, and a bolt engaging said threaded hole for securing the device and said blade to said machine.

5. A device according to claim 4 in which the tapped hole in the oblong member is nearer to one end thereof than to the other.

6. A device according to claim 4 in which the threaded hole is omitted and in which a shank extends from and is formed integral with said oblong member and is provided with a threaded end thereby forming a bolt having said oblong member for a head.

7. In combination a machine blade having flat sides, a cutting face and a bead along the edge opposite said cutting face, an extension member having a bead matching said first bead and flat sides parallel to the sides of said blade, a flat tongue adjacent to said last bead and formed along a face of said extension member, an oblong hole formed partly within said blade and

partly within said extension, a plurality of slotted depressions communicating with said hole, some of said depressions being formed in said blade and others in said extension member, an 5 oblong clamping member positioned within said oblong hole and having extensions engaging some of the depressions in said blades and others in said extension member, thereby retaining the blade and the extension member in definite fixed 10 relation to each other, and means engaging said clamping member for securing said knife and extension to a machine with said flat projecting tongue engaging the usual clearance slot, with said tongue bottoming in said clearance slot to 15 prevent the blade from "cocking".

8. As an article of manufacture, a shear blade having a plurality of oblong holes formed therein, means defining a plurality of slot depressions, having webs therebetween, in said knife communicating with said holes.

9. In a machine knife, means forming an oblong depression communicating with one face of said knife and the back edge thereof, means forming a plurality of curvilinear slots in the face of 25 the knife communicating with said oblong depression along one side thereof and a like plurality of curvilinear slots in the face of the knife communicating with the depression along the other side thereof, an insert member having an 30 oblong body portion and a plurality of extensions projecting from each side thereof and adapted to form a fit with the slots formed in said blade, the spaces between said extensions being equal to the web, between the slots in said 35 knife, said member being of such thickness that when positioned in said depression with the extensions in said slots its outer surface is flush with the face of the knife, a transverse tapped hole formed in said insert member, and means

for securing said member in fixed relation to said knife, whereby the knife may be secured to a machine member by means of a bolt engaging said tapped hole.

10. The invention according to claim 9 in 5 which the end extensions of said member are provided with tapped holes, in which the other extensions and webs between the slots in said knife, each have a continuous hole extending therethrough when the insert is positioned within 10 the depressions, and in which the means for securing the insert member to the knife comprises a pair of dowels having threaded ends, whereby the dowels fit said continuous holes and the threaded portions engage the tapped holes 15 in said nut extensions.

11. The invention according to claim 9 in which the insert member may be positioned within 20 said depression and secured to said knife with its end extensions and one or more of the other extensions projecting beyond the back edge of the knife for the purpose of extending the use of the knife after frequent regrindings.

12. A machine knife or blade having a plurality 25 of oblong slots formed therein, slot depressions also formed therein communicating with said slots, said slot depressions being separated from each other by webs therebetween, means for securing said knife to said machine, said means including a nut member contained within each of 30 said holes and associated slot depressions and having projections engaging at least some of said slot depressions, a series of aligned holes formed in said projections and in the webs between 35 said slot depressions, and a stud mounted in each series of aligned holes for maintaining the nut members in definite fixed relation to said knife.

CHARLES E. G. AFF.
